FREQUENCY MODULATION

James L. Finch, Patchogue, N. Y., assignor to
 Radio Corporation of America, a corporation of
 Delaware

Application April 21, 1938, Serial No. 203,272

22 Claims. (Cl. 179—171.5)

The present application concerns a new and improved means for frequency modulating wave energy. More in particular this invention concerns means for modulating wave energy in frequency in accordance with signals, comprising a frequency determining circuit in which oscillatory energy flows, a transmission line connected at one terminal to said frequency determining circuit and at the other terminal to a variable resistance. 5 The character of the transmission line, frequency determining circuit, and resistance is such that when the resistance is varied at one end of the line a variable reactive effect appears at the other end of the line and in the frequency determining circuit. This change in reactance modulates the frequency of the oscillatory energy flowing in the circuit. The terminal variable resistance is modulated in accordance with the signals it is desired to communicate with. 10 The present invention is simple in nature and structure, economical in operation and effective in accomplishing frequency modulation which accurately characterizes the signals to be transmitted. 15 In describing my invention reference will be made to the attached drawings wherein Figures 1 to 4 inclusive each show a modulation system including the features mentioned above and others. Each modification comprises an oscillator and a line or lines coupling resistances variable at signal frequency to reactive elements in the oscillator to control the frequency of oscillation thereof in a new and improved manner without excessively varying the amplitude of the oscillations generated. 20

Figure 1 shows a specific embodiment of this invention as applied to a crystal oscillator. In this figure, 1 is a crystal oscillator, 18 is a line coupled at one end to said oscillator while K is 25 a modulator coupled to the other end of said line. Returning to the oscillator 1, 2 is a piezo-electric crystal which is connected between grids 3 and 4 of a multi-grid tube 15. As far as the oscillator is concerned grid 4 acts as an anode and grid 3 30 acts as the control grid. A screen grid 5 is placed between these two grids for the purpose of avoiding undesired electrostatic capacity between grids 3 and 4. This oscillator circuit is equivalent to the well known Hartley oscillator in which the crystal with its air gap serves as the inductance and the capacity C between grid 3 and ground in series with the capacity C' between grid 4 and ground serves as the capacity. In this specific application the oscillating portion of the unit is electron coupled to the output portion. The out-

put circuit is comprised of plate 11 and its tuned circuit 12 and 13 from which output power is obtained. Capacity coupling between the oscillatory and the output circuit is minimized by grids 9 and 10 which are placed between grid 4 and plate 11. 5

In connection with my invention additional circuits are connected at point 16 to those already described. These circuits consist of blocking condenser 17, a section of transmission line 18, a tunable circuit consisting of inductance 19 and capacity 20. Shunted across this tunable circuit is the output of vacuum tube 21, in this case shown as a triode. The grid 22 of this tube is modulated by means of telegraph key 23 associated with grid resistor 24 and bias voltage battery 25. When this key is open the grid 22 obtains a working bias voltage through resistor 24 from a point 26 on the bias battery of relatively low negative voltage. When the key is closed a 20 blocking potential from point 27 on the bias battery is applied to the grid 22. 15

The transmission line 18 in this modification consists of a long helix of wire 28 placed near a grounded metal sheet or within a grounded metal tube or other container. 28 has distributed capacity to this grounded sheet or container represented by condensers 29. This line is thus what might be called an artificial line. In this application an artificial type of line is chosen in 30 order to obtain a higher surge reactance than could be obtained with a natural line. The length of this line is adjusted for substantially $\frac{1}{3}$ wave length at the frequency of operation of the oscillator 1 with which it is used. 35

In the operation of this invention tuned circuit 19, 20 is adjusted for a slightly higher frequency than that at which the oscillator 1 is oscillating. Thus, it terminates line 18 in a reactance which is largely inductive. The line is 40 tapped down on coil 19 to a point which will give a suitable value of terminating reactance. When tube 21 is biased to cutoff by closing switch 23 the impedance in which the line is terminated is practically all inductive reactance. Its value 45 can be adjusted as indicated until the terminating reactance matches the surge impedance of the line. When this is done the line will present to the oscillator at point 16 a very high impedance and its effect on the oscillator will be 50 negligible. 55

Now assume that the bias voltage on grid 22 is adjusted until a substantial plate current can flow in this tube. This will make this tube conductive of alternating voltages which it may receive from

the oscillator over line 28 and circuit 19, 20 and thus tube 21 becomes equivalent to a resistance shunted across 19 and 20. Now when the line is terminated in a reactance and a resistance in parallel it no longer has a negligible effect on the oscillator at point 16 but has the effect of paralleling this part of the oscillator circuit with a reactance. This reactance will change the constants of the oscillating circuit and result in a change in oscillator frequency. As the value of resistance introduced by tube 21 varies from infinity to zero the impedance presented by the line at point 16 will vary from infinity to the surge impedance of the line. This impedance will be equivalent to an inductive reactance varying between infinity and the surge impedance of the line in parallel with a resistance which will drop from infinity to about twice the surge impedance of the line and then rise again to infinity. Thus, while sufficient inductance is introduced into the oscillating circuit to change its frequency materially the resistance introduced will not have an effect sufficient to prevent oscillations.

It should be noted that the line 18 acts as a shunt between the grid 4 of the oscillating circuit and ground. Thus it shunts the series capacity C' above, between the grid 4 and ground described above.

Figures 2, 3, and 4 show modifications of the above embodiment of my invention.

In Figure 2 I have added a second line 38 which is connected at point 36 to the control grid 3 of the oscillating circuit. This line thus is shunted across the second series capacity C of the oscillator circuit. It can be made identical with line 18 and it can be connected to circuits identical to circuits 19 to 22 inclusive and thus obtain a greater degree of frequency modulation than can be obtained with only the one line and associated apparatus.

If desired connection can be made only at point 36 instead of point 16. This in some cases will be found more practical and desirable.

As illustrated in Figure 2 line 38 has an effective length of $\frac{1}{8}$ of a wave length. The tunable circuit in which it is terminated represented by 39, 40 is tuned for a lower frequency than that of the oscillator and thus it terminates the line in a capacitive reactance. The line is tapped down on 39 to a point where the value of this reactance is equal to the surge impedance of the line. Now when tube 41 is biased beyond cutoff the reactance presented by line 38 at point 36 will be very high and will have a negligible effect on the oscillator. When the bias on tube 41 is varied between cutoff and its working value the effective resistance shunted across circuits 39, 40 will vary between infinity and some finite value. This will cause the impedance in which line 38 is terminated to vary between a nearly pure capacity reactance and a relatively low resistance. This in turn will cause the impedance presented by the line at 36 to vary between a very high essentially infinite value and a value of capacity reactance approaching the surge impedance of the line. This impedance will consist of the equivalent of a capacitive reactance shunted by a resistance. The value of this resistance will start with infinity, will drop to a value of about twice the surge impedance of the line and will again rise and approach infinity.

The change in impedance shunted between grid 3 and ground as described above will change the frequency of the oscillator in an opposite

direction from that which line 18 changes it as described above. Thus, by differentially biasing tubes 21 and 41 a greater frequency variations can be brought about than would be obtained with either one of these lines and associated circuits.

Figure 2 shows circuits for bringing about this differential biasing effect for telegraphic keying. In this arrangement 41 has its grid 42 connected through resistance 44 to key 48 and through resistances 44 and 47 to tap 52 on a potential divider. Key 48 is used to bias tube 41 in a manner similar to that described above. Tube 21 has its grid 22 connected through resistance 45 to the anode circuit of tube 41 and through resistances 45 and 46 to a point 53 on the potential divider. The cathode of tube 21 is connected to a point 54 on the potential divider while the anode circuit of tube 21 is connected to point 55 on said potential divider. It is noted that the grids of both tubes are negative relative to the cathodes of the respective tubes. When tube 41 is blocked no anode current will flow so that there will be no potential drop across resistor 46. Thus the bias on tube 21 will be as determined by the setting of points 53 and 54 on the voltage divider 50. These points will be set for a working value of bias, i. e., so that current flows in tube 21. Now when tube 41 is made conducting by opening key 48 current will flow through resistor 46 and through the anode of 41. This current will set up voltage across 46 and will cause the voltage impressed on the grid of tube 21 to increase and thus to block tube 21.

Figure 3 shows the manner in which tubes 21 and 41 may be differentially biased when a modulating wave such as that encountered in voice transmission is employed. Here battery 60 is shown supplying anode voltage to tubes 21 and 41 and supplying working bias voltage to the grids of these tubes through the midtap of the secondary of modulation transformer 61. The modulation input connected to the primary of this transformer induces voltages on the grids of 21 and 41 which are opposite to each other. That is, when the grid of 21 becomes more negative the grid of 41 becomes less negative, etc. Thus, these two tubes effect their respective lines so as to swing the frequency in the same direction for a particular modulation input current. This type of modulation will be superior to that obtained if only one of these tubes and its associated circuits were used since the distortion introduced tends to cancel.

The modification in Figure 4 is in principle the same as the modifications in the prior figures. The arrangement in Figure 4, however, differs from the arrangements in the prior figures in that the line 18 connects the anode 73 and a grid 70 of a tube 72 to the electrode 4 of the oscillation generator 15. This circuit is completed as in the prior modification by grounding the cathode of the tube 72 and 15. Keying is accomplished by applying a potential to the grid 74 of tube 72 which varies between ground or other point of fixed potential and a higher negative potential. The operation of this modification otherwise is as in Figure 2.

I claim:

1. A frequency modulation system comprising, an oscillation generator including an electron discharge tube having electrodes, including a plurality of grid electrodes, connected in high frequency alternating-current circuits, a frequency determining piezo-electric crystal connected with 75

two of said grid electrodes, an impedance variable at signal frequency, a transmission line connecting said impedance to said crystal, and means for varying said impedance between a high value 5 and a low value whereby the impedance presented by the line to the crystal varies between a high value and a low value in accordance with variations in said impedance.

2. A frequency modulation system comprising, 10 an oscillation generator including an electron discharge tube having electrodes, including a plurality of grid electrodes, connected in high frequency alternating-current circuits, a frequency determining piezo-electric crystal connected with 15 two of said grid electrodes, an impedance variable at signal frequency, and a transmission line having a terminating reactance which substantially matches its surge impedance connected at one point to said impedance and at another point 20 in shunt to said piezo-electric crystal.

3. A frequency modulation system comprising in combination, an oscillation generator comprising an electron discharge tube having a frequency determining element connected with its electrodes, a reactance tuned to a frequency slightly different than the frequency of operation of said generator, an impedance variable at signal frequency connected with said reactance, and a transmission line connecting said reactance to 25 said element.

4. A frequency modulation system comprising, 30 an oscillation generator including an electron discharge tube having electrodes, including a plurality of grid electrodes, connected in high frequency alternating-current circuits, a frequency determining piezo-electric crystal connected with two of said grid electrodes, an impedance variable at signal frequency, a transmission line having a terminating reactance which substantially matches its surge impedance connecting 35 said impedance to said element, and an output circuit connected with an electrode of said tube coupled to the oscillation generator electrodes by the electron stream only of the tube.

5. A frequency modulation system comprising, 40 an oscillation generator including an electron discharge tube having electrodes, including a plurality of grid electrodes, connected in high frequency alternating-current circuits, a frequency determining piezo-electric crystal connected with two of said grid electrodes, a resistance variable at signal frequency a reactance in shunt to said resistance and a transmission line an odd number of $\frac{1}{8}$ wave lengths long connecting said resistance and reactance to said 45 element.

6. A frequency modulation system comprising, 50 an oscillation generator including an electron discharge tube having electrodes, including a plurality of grid electrodes, connected in high frequency alternating-current circuits, a frequency determining piezo-electric crystal connected with two of said grid electrodes, an impedance variable at signal frequency substantially between infinity and a relatively low value, and a transmission line having a terminating impedance substantially equal to its surge impedance connected at one end in shunt to said impedance and at the other end in shunt to said piezo-electric 55 crystal, said transmission line being an odd number of $\frac{1}{8}$ wave lengths long.

7. A frequency modulation system comprising in combination, an oscillation generator comprising an electron discharge tube having a frequency determining element connected with its elec- 75

trodes, a reactance tuned to a frequency slightly different than the frequency of operation of said generator, an impedance variable at signal frequency connected with said reactance, and a transmission line an odd number of $\frac{1}{8}$ wave 5 lengths long connecting said reactance to said element.

8. A frequency modulation system comprising in combination, an oscillation generator including an electron discharge tube having a frequency determining piezo-electric crystal connected with its electrodes, impedances variable at signal frequency, and a separate transmission line connecting each of said impedances to said crystal. 15

9. A frequency modulation system comprising in combination, an oscillation generator comprising an electron discharge tube having a frequency determining element connected with its electrodes, a plurality of reactances each tuned to a frequency slightly different than the frequency of operation of said generator, an impedance variable at signal frequency connected with each of said reactances, and transmission lines connecting each of said reactances to said element. 25

10. A frequency modulation system comprising in combination, an oscillation generator including an electron discharge tube having a frequency determining element connected with its electrodes, a plurality of impedances variable at 30 signal frequency and substantially identical transmission lines connecting each of said impedances to a different point on said element.

11. A frequency modulation system comprising in combination, an oscillation generator including an electron discharge tube having a frequency determining element connected with its electrodes, an impedance variable at signal frequency, a reactance tuned to a frequency of the order of the frequency of operation of said generator 35 connected in shunt to said impedance and a transmission line connecting said reactance and impedance to a point on said element, said line having an electrical length represented by the formula $(4n+1) \lambda/8$, where n is a whole number including zero and λ is the length of the 40 waves generated. 45

12. A frequency modulation system comprising in combination, an oscillation generator including an electron discharge tube having a frequency determining piezo-electric crystal connected with its electrodes, an impedance variable at signal frequency substantially between infinity and a very low value a transmission line substantially $\frac{1}{8}$ of a wave length long connecting 50 said impedance to said crystal, and a reactance tuned to a frequency of the order of the frequency of operation of said generator connected to the end of said line at which said impedance is connected. 55

13. In a frequency modulation system, an oscillation generator of the electron discharge tube having oscillation generating and frequency determining elements interconnecting the electrodes of the tube, a two wire line connected at 60 one end in shunt to one of said frequency determining elements, an impedance connected to the other end of said line, said impedance substantially matching the surge impedance of the line and comprising an inductance and a capacity in parallel and an electron discharge device 65 impedance variable at signal frequency connected to said other end of said line. 70

14. In a frequency modulation system, an oscillation generator of the electron discharge tube 75

- type having oscillation generating and frequency determining elements interconnecting the electrodes of the tube, a transmission line connected with one of said elements and an impedance terminating said line, said impedance comprising an inductance and a capacity connected with the output electrodes of an electron discharge device variable at signal frequency, said inductance and capacity being tuned to resonate at a frequency slightly higher than the frequency of operation of said generator, said line having a length represented by the formula $(4n+1) \lambda/8$ where n equals zero or a whole number and is the length of the oscillations generated.
15. 15. In a frequency modulation system, an oscillation generator of the electron discharge tube type having oscillation generating and frequency determining elements interconnecting the electrodes of the tube, a transmission line connected with one of said elements, an impedance terminating said line, said impedance comprising an inductance and capacity connected with the output electrodes of an electron discharge device variable at signal frequency, said capacity and inductance being adjusted to resonate at a frequency slightly lower than the frequency of operation of said generator and said line having a length represented by the formula $(4n+3) \lambda/8$ where n is a whole number.
20. 16. In a frequency modulation system an oscillation generator of the electron discharge tube type having electrodes connected in oscillation generating and frequency determining circuits, a first modulating impedance variable at signal frequency, a second modulating impedance variable at signal frequency, a transmission line coupling said first variable impedance to said frequency determining circuit, said transmission line being an odd number of $\lambda/8$ wave lengths long, a second transmission line connecting said second modulating impedance to said frequency determining circuits, said second transmission line being a greater odd number of $\lambda/8$ wave lengths long than said first transmission line.
25. 17. In a frequency modulation system an oscillation generator of the electron discharge tube type having electrodes connected in oscillation generating and frequency determining circuits, a transmission line coupled to said frequency determining circuit, said transmission line being represented by the formula $(4n+1) \lambda/8$, a first terminating impedance comprising an inductance and a capacity and an impedance variable at signal frequency connected to said first transmission line, said inductance and capacity being adjusted to present a negative reactance to said transmission line, a second transmission line connecting said second modulating impedance to said frequency determining circuits, said second transmission line being represented by the formula $(4n+3) \lambda/8$, a second terminating impedance comprising an inductance and a capacity, and an impedance variable at signal frequency connected to said second transmission line, said last named inductance and capacity presenting a positive reactance to its line.
30. 18. In a frequency modulation system, an oscillation generator of the electron discharge device type having electrodes connected in carrier frequency oscillation generating circuits including a frequency determining element, an artificial

line comprising inductances and capacity of values such that the line has a length substantially equal to $(4n+1) \lambda/8$ where n is zero or any whole number and λ is the wave length of the oscillations generated in said device, means connecting one terminal of said line to said frequency determining element, reactances connected with the other end of said line, said reactances substantially matching the surge impedance of the line and an impedance variable at signal frequency connected to the said other end of said line.

19. In a modulation system an electron discharge device generator having its electrodes connected in oscillation generating circuits including a frequency determining element, a modulating device comprising a pair of electron discharge devices having their anodes connected in high frequency circuits and their controlling electrodes connected in push-pull relation to a source of modulating potentials, and a transmission line connecting each of said high frequency circuits to said frequency determining element, said transmission lines each having an electrical length equal to an odd number of $\lambda/8$ wave lengths of the oscillation generated in said first named devices.

20. In a frequency modulation system, an electron discharge tube oscillator having its electrode connected in oscillation generating circuits including as a frequency controlling element a capacity between certain of the electrodes of said tube, a transmission line connected at one end to shunt said capacity, a circuit tuned to a frequency of the order of the frequency of operation of said tube oscillator, means connecting the other end of said line to said tuned circuit to include reactance thereof sufficient to substantially match the surge impedance of the line to its terminating reactance formed by said tuned circuit, and an impedance variable at signal frequency through a wide range connected to said tuned circuit.

21. In a system for producing oscillatory energy and for keying the frequency of the oscillatory energy produced, an oscillation generator including an electron discharge tube having electrodes connected in high frequency circuits including a frequency determining element, a plurality of impedances variable at signal frequency, transmission lines connecting each of said impedances to said frequency determining element, and keying means connected with said impedances.

22. In a system for generating oscillations and for keying the frequency of the oscillations generated in accordance with signals, an electron discharge device of the multi-grid type having electrodes connected in alternating-current circuits, a piezo-electric crystal connected to a pair of said grid electrodes, a plurality of electron discharge tubes each having input and output electrodes, alternating current circuits connected with the output electrodes of each of said tubes, transmission lines connecting said alternating current circuits to said crystal, and means connected with the input electrodes of said tubes for controlling the impedance of the said tubes in accordance with keying signals.
